UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE.

1,149,503.

Specification of Letters Patent. Patented Aug. 10, 1915.

Application filed July 1, 1911. Serial No. 636,382.

To all whom it may concern:

Be it known that I, CHARLES E. DAVIS, a citizen of the United States, residing at Chicago, in the county of Cook and State 5 of Illinois, have invented a certain new and useful Improvement in Mining-Machines, of which the following is a specification.

This invention relates to mining machines and has for its object to provide a new and 10 improved machine of this description.

The invention is illustrated in the accompanying drawings wherein—

Figure 1 is a plan view of one form of mining machine embodying the invention. 15 Fig. 2 is a side elevation of the machine shown in Fig. 1. Fig. 3 is a sectional view taken on line 3—3 of Fig. 2.

Like numerals refer to like parts throughout the several figures.

20 In the drawing I have illustrated a mining machine consisting of a frame 1 carrying a motor 2, and the controlling and feeding mechanism of the machine. Projecting from said frame is a cutter arm 3 about which moves a suitable cutter chain 4 provided with a series of cutters 5. In the operation of the machine some suitable means is provided for feeding the cutters 5 toward the material to be cut. As herein shown the 25 feeding mechanism comprises a flexible power transmitting device 6 which is wound upon a drum 7 and passing around a pulley 8, the outer end thereof being fastened to a fixed device 9. The drum 7 is operatively connected with the motor 2 by means of the gear 10 on the shaft 11, said gear engaging teeth 12 on the interior of the drum. From this construction it will be noted that when the drum 7 is rotated so as to wind the flexible power transmitting device thereon, the 30 machine will be moved laterally toward the fixed device 9. When the machine is in operation, the cutters 5 engage the face of the material to be cut and provide a resistance so that the feeding mechanism hereinbefore 35 described tends to pull the rear end of the machine forward more rapidly than the forward end.

Some suitable means is provided for preventing the too rapid movement of the rear end of the machine and to insure the proper forward feeding of the entire device. As 40 illustrated in the drawing, this result is secured by means of suitable mechanism 45 comprising a drum 13 rotatably mounted

upon the frame and flexible power transmitting device 14 connected with said drum and to a fixed device 15 located on the opposite side of the machine from that on which the fixed device 9 is located. 60

Suitable means are provided for regulating the drum 13 so as to control the unwinding of the flexible power transmitting device in such a manner as to keep the machine in proper position as the feeding mechanism feeds it forward in cutting the material. As illustrated in detail in Fig. 3, the drum 13 is fastened to a sleeve 16 mounted on the shaft 17. A bevel gear 18 is connected with the sleeve 16 so as to rotate therewith. A 70 second bevel gear 19 is loosely mounted on the sleeve 16. A gear 20 is mounted between gears 18 and 19, the gear 20 being provided with openings for the bevel pinions 21 and 22, said pinions being held in place by the 75 pins 23. The gear 20 engages a pinion 24 on the shaft 25. The pinion 24 is operatively connected to the worm wheel 26 by means of the clutch device 27 when said clutch device is in the position shown in 80 dotted lines, and is disconnected therefrom when the clutch is in the position shown in full lines (see Fig. 3). Connected with the bevel gear 19 is a gear 28 which engages the pinion 29 on the shaft 30, which lug is operatively connected with the motor. A worm 31 engages the worm gear 26 and is provided with a shaft 32 which extends rearwardly and which is mounted in the bearings 33 and 34. This shaft is controlled by the handle 35. 85

The use and operation of my machine are as follows: When the machine is in operation the rear end of machine is fed forward by means of the drum 7 and flexible feeding device 6, and is held back from moving forward too rapidly by means of the drum 13 and flexible device 14, the motor 2 acting to rotate both the drum 7 and the drum 13. It is found in practice, however, that some suitable means is necessary to 95 compensate for the different speeds at which the flexible power transmitting device is wound upon the drum 7 and unwound from the drum 13. This variation in speed may be due to various causes, such for example as the varying diameter of the drum 13 as the flexible power transmitting device is unwound. A single rotation of the drum for example when there are two or three layers of the flexible power transmitting device 110

thereon pays out a greater length of the power transmitting device than when there is only one layer thereon, and hence if there is no compensating mechanism the proper forward feeding of the machine is prevented. If for example the flexible feeding device 14 is unwound too rapidly, the rear end of machine will be fed forward too rapidly and the machine will therefore be moved to an inclined position with the cutter arm lagging behind. If, on the other hand, the flexible power transmitting device 14 is unwound too slowly, the cutter arm will be fed forward too rapidly and the machine will take an inclined position with the cutter arm ahead. By means of the present construction, when either one of these conditions occur it is remedied by rotating the handle 35 and the shaft 32 so as to rotate worm 31 and worm gear 26. If for example, the flexible power transmitting device 14 is being unwound too slowly so as to hold back the rear end of the machine, the operator grasps the handle 35 and rotates the shaft 32 so as to rotate the worm 31 and worm gear 26 in a direction to cause the gear 20 to rotate ahead of the gear 28, thus moving the drum 13 faster than it is moved by its connection with the motor, and this is done while the drum is still connected with the motor; for when the worm gear 26 is rotated the gear 20 will be rotated, carrying with it the pinions 21, said pinions moving with relation to the gear 28 by means of the engagement of their teeth with the teeth on said gear 28. If, on the other hand, the flexible power transmitting device 14 is unwound too rapidly so that the rear end of machine is moved forward too rapidly, the operator rotates the shaft 32, worm 31 and worm gear 27 in the opposite direction, thus retarding the rotation of the drum 13 or even winding some of the flexible power transmitting device thereon if necessary until the proper position of the machine is secured. It will thus be seen that by means of this compensating device the rear end of machine may be retarded or its movement speeded up by the operator at will and that this result is secured without disconnecting the retarding mechanism from the motor.

I claim:

1. A mining machine comprising a frame, a cutter projecting therefrom, a motor mounted on said frame, a feeding mechanism for feeding the cutter toward the material to be acted upon, a retarding device for retarding the action of the feeding device, said retarding device operatively connected with said motor, and a manual controlling device adapted to retard or speed up the retarding device without disconnecting it from the motor.

2. A mining machine comprising a frame, a cutter projecting therefrom, a motor

mounted thereon, a feeding mechanism for feeding the cutter toward the material to be acted upon, a drum rotatably mounted upon said frame, a flexible power transmitting device wound thereabout and connected with a fixed part so as to retard the action of the feeding device, an operative connection between said drum and said motor and a compensating device to compensate for the varying diameter of the drum as the flexible power transmitting device is unwound therefrom.

3. A mining machine comprising a frame, a cutter projecting therefrom, a motor mounted on said frame, a feeding mechanism for feeding the cutter toward the material to be acted upon, a drum rotatably mounted on said frame, a flexible power transmitting device connected with said drum and with a fixed part, an operative connection between said drum and said motor, and means for rotating said drum in either direction while it is connected with said motor and independent of the direction of rotation of the motor.

4. A mining machine comprising a frame, a cutter projecting therefrom, a motor mounted on said frame, a feeding mechanism for feeding the cutter toward the material to be acted upon, a drum rotatably mounted upon said frame, a flexible power transmitting device wound about said drum and connected with a fixed part separate from said frame, an operative connection between said drum and said motor, said connection comprising two beveled gears, one connected with the drum so as to rotate therewith, the other adapted to rotate independent of the drum, a connection between said latter beveled gear and the motor, a gear rotatably mounted between said beveled gears, a beveled pinion on said gear and engaging said beveled gears, a worm wheel operatively connected with the gear carrying the beveled pinion, a worm engaging said worm wheel and a controlling part for controlling said worm.

5. A mining machine comprising a frame, a cutter projecting therefrom, a motor mounted on said frame, a feeding mechanism for feeding the cutter toward the material to be acted upon, a retarding mechanism for retarding the action of the feeding mechanism comprising a drum rotatably mounted upon said frame, a flexible power transmitting device connected with said drum, a train of gear wheels operatively connecting said drum with the motor, and a worm and worm wheel associated with said train and adapted to be actuated independent of said motor to vary the speed of said drum.

6. A mining machine comprising a frame, a cutter projecting therefrom, a motor mounted on the frame, a feeding mechanism

for feeding the cutter toward the material to be acted upon, a retarding device for retarding the action of the feeding device, said retarding device operatively connected with 5 said motor, and means for varying the relative speed of the feeding device and the retarding device.

7. A mining machine comprising a frame, a cutter projecting therefrom, a motor 10 mounted on said frame, a feeding mechanism for feeding the cutter toward the material to be acted upon comprising a drum, a flexible power transmitting device wound on said drum and adapted to be connected to 15 a fixed part, a retarding device comprising a drum mounted on said frame, a flexible power transmitting device wound on said drum and adapted to be connected to a fixed part, an operative connection between both 20 of said drums and said motor and means for varying the relative speed of said drums.

8. A mining machine comprising a frame, a cutter projecting therefrom, a motor mounted on said frame, a feeding mechanism for feeding the cutter toward the material to be acted upon, a retarding mechanism for retarding the end of the frame opposite said cutter comprising a drum rotatably mounted upon the frame, a flexible power transmitting device connected with 25 said drum, a connection between the drum and the motor, a worm and worm wheel operatively connected with said drum and separate from the connection between the drum and the motor and adapted to control 30 the speed of rotation of the drum.

Signed at Chicago, Illinois, this 22nd day of June, 1911.

CHARLES E. DAVIS.
